UNITED STATES PATENT OFFICE.

ARTHUR J. LAY, OF RIDGEVILLE, INDIANA.

BROOM.

Application filed April 25, 1924. Serial No. 708,901.

To all whom it may concern:

Be it known that I, ARTHUR J. LAY, a citizen of the United States, and a resident of Ridgeville, county of Randolph and State 5 of Indiana, have invented a certain new and useful Broom; and I do hereby declare that the following is a full, clear, and exact description thereof, reference being had to the accompanying drawings, in which like numerals refer to like parts.

This invention relates to a metal case broom and broom handle connection therefor.

Whereas, heretofore metal case brooms 15 have been formed by using staples or clincher nails for clinching the broom straw in the metal case, the same has not proven entirely satisfactory and would not provide any suitable means for detachably securing 20 a broom handle thereto.

It is the object of this invention, therefore, to employ hollow rivets of relatively large diameter which may be inserted through the casing and broom straw after 25 the latter has been tightly compressed in the casing, in such manner as to displace and force the straw sidewise rearwardly so that it may be firmly held in place by reason of such displacement and compression between the rivets, and between the rivets and 30 ends of the casing. In addition to securing the broom straw in place by this means, the hollow rivets further provide a simple and convenient means for detachably securing 35 the broom handle to the casing.

Another feature of the invention lies in the means for forcing the rivet through the metal case and broom straw so as to cause the broom straw, which is tightly held there- 40 in, to be spread laterally to make room for the hollow rivet, such spreading effecting the compressing and securing action of the straw, as above mentioned.

The full nature of the invention will be 45 understood from the accompanying drawings and the following description and claim:

In the drawings, Figure 1 is a side elevation of a metal case broom with a broom handle secured therein. Fig. 2 is a section taken on the line 2—2 of Fig. 1. Fig. 3 is a perspective side view of the metal case broom with the handle detached. Fig. 4 is a section taken on the line 4—4 of Fig. 3. 50 Fig. 5 is a section taken on the line 5—5 of

Fig. 4. Fig. 6 is a perspective view of the punching member. Fig. 7 is a perspective view of the hollow rivet. Fig. 8 is a view showing the casing and broom straw. Fig. 9 is a view showing the rivet having been 60 inserted therein with the punching member partially withdrawn therefrom.

In the drawings there is shown a metal case broom comprising the broom straw portion 10, which is stitched in the usual manner at 11, and which is secured and held rigidly in place by the metal cap or casing 12 in the usual manner. The broom straw is inserted and compressed within the metal cap, as has been heretofore customary, but 70 the usual stapling thereof is dispensed with, the broom straw being secured in the cap by the hollow rivets 13, as shown in Figs. 4 and 5.

The metal cap may or may not be punched 75 out to receive the rivets, although the former method is preferable. After the metal cap has been secured about the upper part of the broom so as to compress the broom straw tightly therein, it is placed upon a punch press to receive the rivets. For the purpose of inserting the rivets through the metal case and tightly compressed broom straw, there is provided a punching member 80 having a sharp pointed end 14, adapted to penetrate between the broom straw and spread it, as well as penetrate the metal cap if necessary. The sharpened end of the punching member is provided with a shank 85 15 of such size and diameter as to receive 90 the hollow rivet 13.

A punch press of proper construction having a punching head 16 is adapted to force the sharpened end of the punching member, by engagement with its shank 15, through 95 the metal case and broom straw, as shown in Fig. 8, spreading the latter laterally, until the hollow rivet 13 has passed therein, as shown in Fig. 9, after which the punching member may pass on through the rivet 100 and freely drop out from the under side of the broom, leaving the rivet in place. The usual means is thereafter employed for punching the ends of the rivets, as shown in Fig. 4, for securing said rivets in place. 105

It will be noted, as shown in Fig. 5, that the appreciable diameter of the rivets will cause the straw to be spread laterally and distorted out of their longitudinal plane, 110 and as said rivets may be positioned in stag-

gered relation with each other, the straw will not only be squeezed more tightly in the casing, but will assume a rather curved position tending to more securely hold it in place.

The metal case broom is then completed and may be sold or shipped to users who are supplied with the detachable broom handles 17, having a metal bifurcated head 18 which may be readily slipped over the casing. As the head 18 is provided with openings corresponding to the position and diameter of the hollow rivets, said head may be readily attached to the broom by securing the bolts 19 through the head 18 and rivets 18, as shown in Fig. 2. Upon the broom being worn out, the bolts 19 may be

removed, and a new broom head inserted in the head 18 and secured to the handle, as above described.

20

The invention claimed is:

The combination of a body of broom straw, a metal casing embracing one end of the straw, a plurality of tubular rivets extending through said casing and straw for spreading and wedging the straw therein, a handle, a bifurcated cap secured to said handle and embracing said casing, detachable members adapted to extend through said cap and tubular member for detachably securing the handle to said broom head.

25

In witness whereof, I have hereunto affixed my signature.

ARTHUR J. LAY.
